UNITED STATES PATENT OFFICE.

THOMAS H. BLAIR, OF NORTHBORO, MASSACHUSETTS.

HYDROCARBON-LAMP.

SPECIFICATION forming part of Letters Patent No. 700,475, dated May 20, 1902.

Application filed February 7, 1899. Serial No. 704,793. (No model.)

To all whom it may concern:

Be it known that I, THOMAS H. BLAIR, a citizen of the United States, residing at Northboro, in the county of Worcester and State of Massachusetts, have invented a new and useful Hydrocarbon-Lamp, of which the following is a specification.

The aim of this invention is to provide a new and improved hydrocarbon-lamp in which the parts shall be simply and conveniently arranged, in which the supply of oil or liquid shall be automatically regulated, and in which the oil and vapor can be quickly shut off and controlled when it is desired to extinguish the lamp.

To these ends my invention consists of the combinations and devices described in this specification and illustrated in the accompanying four sheets of drawings, in which—
20 Figure 1 is a side view, partially broken away, showing the connection of two lamps constructed according to my invention with an oil-tank. Fig. 2 is a sectional view of my preferred form of lamp. Fig. 3 is a plan view
25 of the perforated burner-plate. Fig. 4 is a sectional view at right angles to Fig. 1 of the vaporizing-chamber. Fig. 5 is a plan view of the vaporizing-chamber. Fig. 6 is a view similar to Fig. 1, illustrating a modified form
30 of construction; and Fig. 7 is an enlarged detail view showing the positive shut-off valve in its closed position.

My improved lamp consists of a vaporizing-chamber located above a suitable burner, in which chamber is placed a diaphragm which connects to a valve controlling the supply, so that the pressure generated in the vaporizing-chamber will automatically regulate the oil-supply. A double-valve system is also provided in connection with suitable operating means, so that when the lamp is extinguished the supply of vapor from the vaporizing-chamber to the burner will be cut off and simultaneously the supply of oil to the vaporizing-chamber will be positively stopped.

The invention also consists of certain improved details of construction hereinafter recited, and more particularly pointed out in the claims.

50 Referring to the drawings and in detail, I

will first describe the preferred form of lamp illustrated in the first two sheets of the drawings.

10 designates a vaporizing-chamber, which I have shown made circular in form. In the top of this chamber is arranged a ledge 11, and screwed into the top of the chamber is a perforated cap 12. Arranged between the ledge 11 and the cap 12 is an asbestos packing and a diaphragm 13.

14 designates a supply-pipe, and the same may have a suitable valve 15. The supply-pipe 14 is screwed into a suitable boss extending from the vaporizing-chamber. Extending from this boss is a feed-pipe 16, which is bent around, as shown in Fig. 4, so as to be flexible. The end of the feed-pipe is fitted into the side of a small hollow cup or cylinder 17, which has a valve-seat arranged on the top thereof. This cylinder 17 is connected by suitable straps 18 to the diaphragm 13, so that the same will move up and down with the said diaphragm.

19 designates a square yoke which surrounds the cylinder 17. The under side of said yoke forms a valve and has a cushion 20, made out of asbestos or other suitable material, arranged to engage the valve-seat formed on the top of the supply-cylinder 17. A pin 21 is preferably arranged to project from said valve 20 down through the valve-seat formed on top of the cylinder 17, so as to prevent by movement of the diaphragm or operating-handle any impurities clogging said valve. On the lower side of said yoke 19 is arranged another asbestos cushion, which forms a valve 22. Said valve 22 is set to coöperate with the upper end of a tube 23, which extends up into said chamber 10 to form a valve-seat and a trap to retain the oil in the chamber. This is an advantageous construction in that a certain amount of oil will be trapped or held on the bottom of the chamber up to the top of the tube 23, so that a large surface of the same will be exposed to the heat of the lamp.

Extending from the yoke 19 down through the tube 23 is a rod 24, the lower end of which is threaded into an operating-handle 25. This operating-handle 25 is fitted into the lower end of the tube 23. The lower end of the tube

23 is fitted into a hub 27. The handle and tube are kept in place by means of one or more pins 26, which are driven through said hub and said tube and which fit into an annular groove cut in the shank of the screw-handle 25, as shown. By this means as the screw-handle is turned the rod 24 can be raised or lowered.

The tube 23 has small outlet-holes 28, which permit the vapor to pass out into a suitable chamber for mixing the vapor and air, my construction having a base 29, which is secured to the hub 27 by pins or braces 30. The upper end of the base 29 is provided with a perforated plate 31, and the shoulder of the base 29 is provided with a suitable ring of wicking or absorbent material 300, which may be filled with alcohol and lighted when it is desired to start the lamp into operation. A suitable mantle 32 is arranged between the bottom of the vaporizing-chamber and the plate 31.

A collar 33 may be held on the base 29 by suitable clips 34, and this collar may support a chimney 36 and a porcelain cup 35. A shade 37 may also be arranged to protect the upper part of the lamp and can be secured to the vaporizing-chamber by means of suitable screws 38.

The operation is as follows: The lamp is started into operation by saturating the wicking 300 with alcohol and lighting the same. At the same time the screw-handle 25 is operated to raise the valves 20 and 22 from their seats. Oil will then pass up over the valve-seat formed on top of the cylinder 17 and will drop onto the bottom of the vaporizing-chamber 10 and will there be converted into vapor, which will fill the chamber, and the excess passing under pressure down through the tube 23 will be forced out through the holes 28 up into the base 29. As the same rushes up into the burner outside the tube 23 air will be drawn into the bottom of the base and mixed with the vapor, which mingled vapor and air will be ignited by the alcohol-flame and will burn above the plate 31. This will continue the heating and generating of vapor until the supply of alcohol will have burned out, when the lamp will continue in operation. This will render the mantle 30 incandescent and will give a brilliant light. When pressure is increased beyond a desirable point in the vaporizing-chamber 10, the diaphragm 15 will be pushed upward. This will raise the cylinder 17 against the valve 20, and this action will automatically regulate the supply of oil to the vaporizing-chamber by shutting off the supply of oil when the desired pressure is obtained and by opening to allow oil to enter the vaporizing-chamber when the pressure falls or by keeping the valve in such position that the supply will be set to just feed the proper amount of oil to keep the pressure substantially constant. When it is desired to extinguish the lamp, the screw-handle 25 is

operated to draw the valves 20 and 22 to their seats. This action will simultaneously stop the supply of oil to the vaporizing-chamber and the supply of vapor to the burner.

The arrangement of cylinder 17 and flexible feed-pipe 16 is a very desirable one, because by this construction the oil is brought to a high temperature before it is allowed to escape into the vaporizing-chamber, and the cylinder 17 thus forms a small reservoir of heated oil, which is ready for use the instant the diaphragm descends and allows the escape of the same between the valve-seat and the valve 20.

In Fig. 5 I have shown a modification. In this modification the supply-pipe 16 is brought down under the vaporizing-chamber 10 and is carried up into a valve-chamber 40, formed on the inside of the vaporizing-chamber. Fitting loosely in the valve-chamber 40 and bearing on a seat formed therein is a small valve 41, which is arranged on the end of a link 42, which link is connected to the rod 24 and is pivoted at its center to a bracket 43. The upper end of the rod 24 in this construction is connected to the diaphragm. The lower end of the rod in this construction rests upon but is not connected with a taper plug 44, formed on the shank of the screw-handle 25. The screw-handle in this modification is threaded into the lower end of the tube 23, and the shank of the screw-handle is formed with the taper plug 44, which co-operates with a correspondingly-tapered seat through which the holes 28 are bored, so that when the tapered plug 44 is screwed up it will cut off the supply of oil to the openings 28. In this construction pressure generated in the vaporizing-chamber will by pressure on the diaphragm operate the valve 41 to automatically regulate the supply of oil. When it is desired to extinguish the lamp, the screw-handle 25 is turned. This will push up on the rod 24 and will force the valve 41 to its seat, thus closing the supply of oil. At the same time the plug 44 will come to its seat and will thus close the opening 28 and will thus stop the supply of vapor to the burner and extinguish the lamp. Thus a double valve is formed by this construction—one valve, which automatically regulates the supply of oil and which may be positively closed, and a second valve, which may be simultaneously positively closed with the first valve to stop the supply of vapor to the burner.

The details herein described may be varied from by skilled and artistic mechanics to form a table-lamp or one to be suspended from the ceiling without departing from the scope of my invention as expressed in the claims. In modifying the construction for a suspension-lamp the feed-pipe 16 can be carried up around through the cap 12, to which cap a supply-pipe extending from the ceiling can be screwed. The construction shown, however, is preferred, as with the same the cap 12 can be un-

screwed to get at the working parts in the chamber without interfering with the supply pipe or lamp.

In some cases an extra number of vapor pipes can be carried from the vaporizing-chamber to other burners, and thus form a chandelier.

Having thus fully described my invention, what I claim, and desire to secure by Letters

10 Patent of the United States, is—

1. The combination in a hydrocarbon-lamp, of a vaporizing-chamber, a burner arranged to be fed by vapor from said vaporizing-chamber, a pipe connected to the vaporizer to supply oil thereto, a valve controlling the flow of oil in such pipe, and a diaphragm exposed to the pressure generated in the vaporizing-chamber, and connected to operate said valve to increase the flow as said pressure falls and

20 to diminish said flow as the pressure increases.

2. The combination in a hydrocarbon-lamp, of a burner, a vaporizing-chamber, a pipe connected to the vaporizer to supply oil thereto, a valve controlling the flow of oil in such pipe, and a diaphragm forming the top of the vaporizing-chamber, and connected to operate said valve to increase the flow as the pressure in the vaporizing-chamber falls, and to diminish said flow as the pressure increases.

3. The combination in a hydrocarbon-lamp, of a burner, a vaporizing-chamber, a regulating-valve automatically controlling the supply of oil to the vaporizing-chamber, a pipe or tube between the vaporizing-chamber and burner, a valve controlling the passage of vapor through said pipe, and operating means for closing both valves to shut off the supply to the vaporizing-chamber and the passage of vapor to the burner, substantially as described.

4. The combination in a hydrocarbon-lamp, of a vaporizing-chamber, a burner arranged to be fed by vapor from said vaporizing-chamber, a pipe connected to the vaporizer to supply oil thereto, a valve controlling the flow of oil in such pipe, means operating from the pressure generated in the vaporizing-chamber for controlling the valve, and thereby the supply of oil, and operating means for positively closing said valve.

5. The combination in a hydrocarbon-lamp, of a burner, a vaporizing-chamber, a supply pipe, a regulating-valve automatically controlling the supply of oil for the vaporizing-chamber, a connection between the vaporizing-chamber and burner, a valve controlling the passage of vapor through said connection, and suitable operating means arranged to open and close both valves, so that when the valves are open, the valve controlling the supply will be free to work, to automatically regulate the supply of oil, substantially as described.

6. The combination in a hydrocarbon-lamp, of a burner, a vaporizing-chamber located above the burner, a tube extending from the

chamber to the burner, a mantle arranged around the tube, a valve controlling the supply admitted to the vaporizing-chamber, a rod extending from said valve through said tube, and operating means at the bottom of the lamp for said rod, substantially as described.

7. The combination in a hydrocarbon-lamp, of a burner, a vaporizing-chamber, a tube extending from the chamber to the burner, a mantle arranged around the tube, an automatically-operating valve controlled by the pressure in the chamber for regulating the supply of oil, a rod extending from said valve through said tube, and operating means at the bottom of the lamp arranged to open and close said valve, and to leave said valve, when open, free to automatically operate, substantially as described.

8. The combination in a hydrocarbon-lamp, of a burner, a vaporizing-chamber, a tube extending from the chamber to the burner, a mantle arranged around the tube, a valve controlling the supply to the chamber, a valve controlling the passage of vapor from the chamber to the burner, a rod extending from said valves through said tube, and operating means for said rod at the bottom of the lamp, substantially as described.

9. The combination in a hydrocarbon-lamp, of a burner, a vaporizing-chamber, a tube extending from the vaporizing-chamber to the burner, a mantle arranged around the tube, an automatically-operating valve controlled by the pressure in the chamber for regulating the supply of oil, a valve controlling the passage of vapor from the chamber to the burner, a rod extending from said valves through said tube, and operating means for said rod arranged to open and close said valves, and to leave the oil-supply valve free to automatically operate when open, substantially as described.

10. The combination in a hydrocarbon-lamp, of a vaporizing-chamber, a cylinder flexibly connected to the oil-supply, and movably mounted in said chamber, a valve, and a diaphragm connected to said cylinder.

11. The combination in a hydrocarbon-lamp, of a vaporizing-chamber, a cylinder flexibly connected to the oil-supply, a valve, a diaphragm connected to move said cylinder, and positive operating connections for said valve.

12. The combination in a hydrocarbon-lamp, of a vaporizing-chamber, a cylinder arranged in said chamber, and flexibly connected to the oil-supply, a yoke carrying two valves, one engaging the cylinder, and the other regulating the passage of vapor from the chamber, and operating means for said yoke, substantially as described.

13. The combination in a hydrocarbon-lamp, of a vaporizing-chamber, a cylinder therein flexibly connected with the oil-supply, a diaphragm connected to said cylinder, a yoke carrying two valves, one engaging said

cylinder, and the other controlling the passage of vapor from the vaporizing-chamber, and operating means for said yoke, substantially as described.

5 14. The combination in a hydrocarbon-lamp, of a vaporizing-chamber, a cylinder therein flexibly connected with the oil-supply, a diaphragm connected to said cylinder, a tube extending from said chamber, a yoke 10 carrying two valves, one engaging said cylinder, and the other engaging the end of said tube, and operating means for said yoke extending through the tube, substantially as described.

15 15. The combination in a hydrocarbon-lamp, of a vaporizing-chamber, a movable cylinder therein flexibly connected with the oil-supply, and having a valve-seat on top thereof, and a valve coacting therewith and 20 having a pin projecting into said cylinder, substantially as described.

16. The combination in a hydrocarbon-lamp, of a vaporizing-chamber, a cylinder arranged therein, and flexibly connected to the 25 oil-supply, a diaphragm connected with said cylinder, a yoke carrying two valves, one en-

gaging said cylinder, and the other controlling the passage of vapor from said chamber, a tube extending from said chamber, a rod extending through said tube and connected to said yoke, and an operating-handle at the bottom of said tube, substantially as described.

17. In a vapor-burning lamp, an oil-tank, a vaporizer connected to receive oil therefrom, and a burner arranged to be fed by vapor from said vaporizer, and to heat said vaporizer, in combination with a regulating-valve controlling the flow of oil from the tank into the vaporizer, and a regulator for said valve 40 controlled by the varying pressure of vapor in the vaporizer for moving the valve to increase the flow as said pressure falls, and to diminish said flow as the pressure increases.

In testimony whereof I have hereunto set 45 my hand in the presence of two subscribing witnesses.

THOMAS H. BLAIR.
